UNITED STATES PATENT OFFICE.

JOHN M. COFFIN, OF DANIELSVILLE, PENNSYLVANIA.

DESIGN FOR SLATE-FRAME.

Specification forming part of Design No. 6,684, dated May 27, 1873; application filed April 22, 1873.

To all whom it may concern:

Be it known that I, JNO. M. COFFIN, of Danielsville, in the county of Northampton and State of Pennsylvania, have invented certain new and useful Improvements in Design for Slate-Frames; and I do hereby declare that the following is a full, clear, and exact description thereof, reference being had to the accompanying drawing and to the letters of reference marked thereon which form a part of this specification.

The nature of my design is fully illustrated in the accompanying drawing; and it consists in an oval or round-cornered slate-frame having a molded outer edge, and also in an oval or round-cornered slate-frame having a molded outer edge and a beaded inner edge.

A A represent my slate-frame. The corners are rounded, as shown, so as to form an

oval or round-cornered frame. The outer edge B of the frame is molded and the inner edge C is beaded where the slate comes in contact with the frame.

What I claim is—

1. The design for an oval or round-cornered slate-frame having the molding around the outer edge of the form, shown and described.

2. The design for an oval or round-cornered slate-frame having the molding around the outer edge and beading around the inner edge of the form, herein shown and described.

In testimony that I claim the foregoing as my own I affix my signature in presence of two witnesses.

JOHN M. COFFIN.
